UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING.

1,256,821.

Specification of Letters Patent. Patented Feb. 19, 1918.

Application filed June 14, 1917. Serial No. 174,678.

To all whom it may concern:

Be it known that I, JOHN F. O'CONNOR, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part 10 of this specification.

This invention relates to improvements in side bearings.

The object of the invention is to provide a side bearing for railway cars wherein the 15 anti-friction members are automatically returned to normal after each actuation by means supported entirely by the anti-friction members themselves and independently of any external member.

20 In the drawing forming a part of this specification, Figure 1 is a longitudinal sectional view of a side bearing showing my improvements in connection therewith, the bearing being applied to the truck bolster of 25 a car. And Fig. 2 is a transverse vertical sectional view, taken substantially on the line 2—2 of Fig. 1.

In said drawing, 10 denotes the upper portion of a truck bolster and 11 the under 30 side of a body bolster. As shown, the improved side bearing A is preferably attached to the truck bolster and comprises a base casting having lower wall 12, parallel side walls 13—13 and curved end walls 14—14.

35 The bottom wall of the base casting is provided with two bearing seats or surfaces 15—15 on which are rockably mounted two anti-friction rockers 16—16. The rockers 16 are held within the base casting by pins 17 40 which extend through the side walls of the casting and are held from accidental removal by cotters 18. Each of the rockers 16 is provided with an upper cylindrical surface 19 adapted to engage the under surface 45

face of the body bolster 11. Furthermore, each of the rockers 16 is provided at the center thereof with an opening 20, the walls surrounding and defining said opening being oppositely curved, as indicated at 21 50 on the lower side and 22 on the upper side. The openings or recesses 20 are just large enough to receive an elongated plate spring 23 which is extended through both of said openings. At its ends, the spring 23 is preferably curved, as indicated at 24, to thereby

prevent accidental disengagement from the rockers.

The normal condition of the plate spring 23 is flat, as shown in Fig. 1. As the rockers 16 are moved to either side of normal, it is 60 apparent that the spring 23 will be deflected downwardly by each of the rockers on one side of a vertical plane passing through the axis of each rocker and will be deflected upwardly by each of the rockers on the opposite side of said planes. This will place the spring 23 under tension and, upon release of the pressure on the rockers, the spring will tend to straighten itself and in so doing will return the rockers to normal position. With this arrangement, it is apparent 70 that the spring means for returning the rockers to central normal position are carried entirely by the rockers themselves and independently of the base casting or other 75 members. The end walls 14 of the base casting are curved in the manner shown to provide proper clearance for the rockers as the latter are moved from normal position and the side walls of the base casting may be recessed, as indicated at 25—25 to form vents 80 for the cleaning out of dirt or other foreign matter.

I claim:

1. In a side bearing, the combination with 85 a member having bearing surfaces for a plurality of anti-friction members, of a plurality of anti-friction members movable from normal position when actuated, and means carried entirely by said anti-friction members 90 adapted to automatically return the latter to normal position after removal of the pressure thereon.

2. In a side bearing, the combination with 95 a member having bearing surfaces for a plurality of rockers, of a plurality of rockers mounted on said bearing surfaces, and means carried entirely by said rockers adapted to automatically return the latter to normal position after actuation thereof.

3. In a side bearing, the combination with 105 a casting adapted to be secured to a bolster and having a plurality of bearings formed therein, of a plurality of anti-friction members mounted on said bearings, and means for automatically returning said members to normal position after removal of the pressure thereon, said means being supported entirely by said members.

4. In a side bearing, the combination with 110

a member having bearing surfaces for a plurality of rockers, of a plurality of rockers mounted on said bearing surfaces, and means carried entirely by said rockers adapted to automatically return the latter to normal position after actuation thereof, said means including a spring plate extending through said rockers.

5. In a side bearing, the combination with
10 a hollow base casting adapted to be secured to a bolster and having a pair of bearings in

the bottom thereof, of a pair of rockers supported on said bearings, said rockers being centrally recessed, and a plate spring extending through said recesses, said spring being adapted to be flexed by the rockers as the latter are moved from normal position.

In witness that I claim the foregoing I have hereunto subscribed my name this 26th day of May, 1917.

JOHN F. O'CONNOR.
